UNITED STATES PATENT OFFICE.

EDWIN FARGO, OF WASHINGTON, PENNSYLVANIA.

HOT-BLAST VALVE.

No. 843,935.

Specification of Letters Patent.

Patented Feb. 12, 1907.

Application filed April 17, 1906. Serial No. 312,073.

To all whom it may concern:

Be it known that I, EDWIN FARGO, a citizen of the United States, residing at Washington, in the county of Washington and State of Pennsylvania, have invented certain new and useful Improvements in Furnace Apparatus, of which the following is a specification.

The invention relates to regenerator furnace apparatus, and has for its objects; to provide a controlling means for the admission of air and the outflow of the products of combustion adapted to prevent any leakage; to provide a controlling means whereby the escape of air or gas direct to the stack is prevented during the reversal of the controlling means; to provide a valve for the admission of gas wherein all burning of the gas at the valve, and consequent overheating and warping thereof is avoided, and finally, to provide a valve positive in its action and so arranged as to be operable by the workman from a position distant from the valve. The invention is illustrated in its preferred form in the accompanying drawings, in which—

Figure 1 is a plan view of the controlling means or valve, which construction is used preferably where natural gas is used;

Figure 2 is a transverse section through the center of the valve shown in Figure 1;

Figure 3 is a plan view of a double valve, which valve is used where artificial gas is used in place of natural gas;

Figure 4 is a diagrammatic plan view showing the construction of the furnace when provided with the double valve, and

Figure 5 is a transverse section through the furnace on the line (V)-(V) of Figure 4, the controlling valve being shown however, in end elevation instead of section.

The invention which resides in the controlling means shown in detail in Figures 1, 2 and 3, is intended to be used in connection with the ordinary and well-known Siemens regenerator furnace shown in Figures 4 and 5 of the drawing. This furnace is of the ordinary type, but will be briefly described in order to make clear the application of my controlling means. As shown in Figures 4 and

5, A, B, C, and D, are the regenerators which are placed below the combustion chamber E, and have connection with such chamber, at their tops, and are connected at their bottoms or ends with the passages 6, 7, 8, and 9, which passages lead to the stack passage 10,

connected at its outer end with the stack F. The controlling means or double valve G is interposed in these passages, and controls the flow of air, gas, and the outgoing products of combustion.

As shown in Figure 4, the air enters the valve G at the opening 11, passing through the valve to the passage 6, thence through the regenerator A to the chamber E. The products of combustion then pass through the regenerators C and D, the passages 9 and 8, the valve and the stack passage 10, to the stack. The artificial gas enters at the opening 12, passes through the valve to the passage 7, thence through the regenerator B to the combustion chamber E. The products of combustion then pass through the regenerators C and D, passages 8 and 9, the valve G, and the stack passage 10. When the valves are reversed, the flow of gas and air is of course, reversed, and the gas is carried through the passage 9, regenerator furnace C, and combustion chamber E. The products of combustion then pass through the regenerators A and B passages 6 and 7, the valve, and the passage 10. The air is carried through the passage 8, regenerator D, and combustion chamber E. The products of combustion then pass through the regenerators A and B, passages 6 and 7, the valve and the passage 10. The valves are provided with connecting gearing operated by a sprocket chain 13 and sprocket 14, whereby the air and gas may be reversed simultaneously from a position adjacent the operator's bench. The general arrangement of the parts now having been thus described, description will now be made of the controlling means G in which the invention resides.

In Figure 3 a plan view of the double valve adapted for use with artificial gas is shown, and in Figure 2 a transverse section is shown, which although taken through Figure 1, applies, with the exception of the element of gearing, to each of the valves shown in Figure 3. These valves, the one for the admission of gas and the other for the admission of air, are identical in construction, so that a description for one will suffice for both. As shown in Figure 2, each of these valves comprises a casing 14 provided at its ends with manholes 15, and on its lower side with the openings 16, 17, and 18. The openings 16 and 18 lead to the regenerator passages, while the opening 17 leads to the stack. 11

The casing is also provided on its upper side with a flanged admission casing 19 provided with a race 20 constituting the lower member of a ball bearing. Seated transversely of the admission casing 19 and the opening 17 is the rotary valve member 21 for controlling the direction of flow. This transverse valve comprises a cylindrical member having a pair of perforations 22 and 23 in line with each other and adapted to connect the interior of the cylindrical member 21 with either side of the passage in the casing 14, and also to connect either side of such passage in the casing 14 with the opening 17 which leads to the stack. Extending obliquely of the cylindrical member 21 is a partition wall 24 which extends from the lower side of the opening 22 to the upper side of the opening 23. The upper end of the cylindrical member 21 is provided with a projecting flange adapted to rest upon the top of the balls 25, thereby affording an antifriction bearing. This flange portion is also provided with a bevel gear 26 adapted to engage an operating bevel gear 27. In the position shown in Figure 2, assuming that the valve is the one for admitting air, the air passes down through the member 21, opening 22, and opening 16, from which the air circulates through the regenerators and furnace, and returns to the opening 18, after which it passes through the opening 17 to the stack. Now if the valve is revolved 180° the opening 22 will connect the right hand side of the casing 14 with the passage 21, while the left hand side of the casing 14 will be connected with the opening 17. When in this position the direction of flow through the regenerators and furnace is reversed. When the valve constitutes the gas control the operation is of course substantially the same. It will be seen that by virtue of the contacting cylindrical surfaces my valve is absolutely tight, and that there is no leakage as in the case of the old butterfly valve, which is pivoted on a horizontal axis in the manner of a damper. It will also be seen that in my valve there is never any direct connection between the admission passage and the passage 17 to the stack during the reversal of the valve. This is not the case in the butterfly valve, as when such valve occupies its intermediate or vertical position the fluid admitted instead of going through the regenerator passages goes straight through to the stack. This is a small matter for the air admission, but for the gas admission such loss caused by direct leakage to the stack is an important matter. It has been remedied with the butterfly valve heretofore by using an additional valve in the stack which could be closed during the reversal of the butterfly valve, but it will be seen that my single valve accomplishes the desired function without any additional closing means for the stack.

It will also be seen from inspection of Fig. 2 that when gas is being admitted through the passage 21 and openings 22 and 16, that the hot products of combustion from the furnaces are passing adjacent to the partition 24. With the old form of butterfly valve a slight leakage always occurred adjacent the valve, and the gas burned around the edges of the valve thereby overheating the valve and causing it to warp. In my valve there is no danger of such leakage and overheating. It will furthermore be apparent that by the use of a cylindrical valve braced by the transverse member 24, all danger of warping is obviated, which construction is a decided improvement over the flat butterfly valve with its great tendency to warp and thereafter fit unevenly. In Fig. 3 I have shown the means whereby the gears for operating the rotary valve are connected. The gears for operating the rotary valves, which gears correspond to the gear 27 of Figure 2, are mounted upon a shaft 28, which shaft carries a bevel gear 29 engaging the gear 30 mounted upon the shaft 31. This shaft carries a sprocket 32, which sprocket, as indicated in Figure 4, is connected to the sprocket 14 by means of the sprocket chain 13, thereby affording means for operating the two valves simultaneously from a position adjacent the operator's bench.

When the single valve shown in Figure 1 is used the construction of Figure 4 is modified so that there are only two regenerators, as A and D, and the gas, which is in this case natural, is admitted directly to the combustion chamber E. The operation and construction of this single valve is substantially the same as that for the air admission half of the double valve heretofore described, with the exception that the sprocket 33 is mounted directly upon the shaft 34 which carries the gear 27. In order to protect the gearing and bearings from dust and contact with the gases I provide in both the double and single valve a casing 25, which fits down over the admission casing in the manner indicated in the drawing.

Having thus described my invention and illustrated its use, what I claim as new, and desire to secure by Letters Patent, is the following:

1. In combination in regenerator apparatus, a casing having a transverse passage enlarged at its top and provided with a shoulder, a tubular perforated valve member fitting therein and provided with a projecting annulus fitting the enlarged portion of the casing and comprising a bevel gear on the upper side and a bearing on the lower side seated rotatively on the shoulder, a power shaft journaled in the enlarged portion of the casing and carrying a beveled gear for driving the gear on the annulus, and a protective casing resting upon the top of the valve cas- 130

ing and upon the top of the valve whereby a tight joint is provided and the gears and bearings protected.

2. In combination in regenerator apparatus, a casing having a transverse passage enlarged at its top and provided with a shoulder, a tubular perforated valve member fitting therein and provided with a projecting annulus fitting the enlarged portion of the 10 casing and comprising a bevel gear on the upper side and a bearing on the lower side resting rotatively upon the shoulder, interposed antifriction balls, a power shaft journaled in the enlarged portion of the casing

and carrying a beveled gear for driving the 15 gear on the annulus and a removable protective casing resting upon the top of the valve casing and upon the top of the valve whereby a tight joint is provided and the gears and bearings protected. 20

In testimony whereof I have hereunto signed my name in the presence of the two subscribed witnesses.

EDWIN FARGO.
